UNITED STATES PATENT OFFICE.

THOMAS GORDON, OF PHILADELPHIA, PENNSYLVANIA, ASSIGNOR OF ONE-HALF TO EMANUEL STEIN, OF SAME PLACE.

GAS-GOVERNOR.

SPECIFICATION forming part of Letters Patent No. 315,496, dated April 14, 1885.

Application filed June 7, 1884. (No model.)

To all whom it may concern:

Be it known that I, THOMAS GORDON, of the city of Philadelphia, State of Pennsylvania, have invented a new and useful Improvement 5 in Gas-Governors, of which the following is a specification.

My invention relates to governors for regulating the flow of gas from a supply-pipe to the burner; and it consists of the combination 10 of devices hereinafter described, whereby the flow and pressure of gas through the governor are regulated and controlled by means of a perforated valve receiving the pressure against its vertical sides, and by regulating-screws, or by an automatic slide-valve device. 15

In the accompanying drawings, Figure 1 is a front elevation of my gas-governor; Fig. 2, a vertical section through the center, showing the construction and operation of the several parts; and Fig. 3 a like vertical section 20 showing a modification of a part of the device in which the regulating-screws are omitted and an automatic sliding valve arrangement substituted therefor.

The shell of the governor consists of two 25 hollow cups, A and B, screwed together at c c, each provided with mouths or ends a and b, which cups are screw-threaded at their respective ends to attach to the gas supply and exit pipes. The lower cup, B, is provided 30 internally with a hollow cylindrical extension-piece, C, which supports a flanged plate, D, having on its under side a hollow cylindrical extension, E, constituting the valve-chamber. This extension E rests within the 35 cylindrical chamber C. The plate D has a central opening, which is made as a valve-seat, and it is securely attached to the extension-piece E, which is perforated at o o to permit the passage of gas, and it is also screwed 40 to the top of the cylindrical chamber C, and forms a gas-tight connection therewith.

Projecting upward from the internal base 45 of the chamber E is a guide-rod, d, placed concentrically with the vertical side of the chamber, and passing through the valve e, disk D, and screw m. This screw is recessed its whole length, except the head, so that the guide-rod will not touch its sides, excepting 50 only through the head, and that only by a knife-edge, and the valve-recess is made in

the same manner, except a very small part in its extreme base, for the same purpose, in order that the action of the valve and disk may not be impeded by unnecessary friction 55 of the parts. The valve e may be cylindrical in form on its outer side, or conical, as shown in the drawings, and has a cylindrical neck supporting a disk, G, which is secured thereto by a screw, m, and is provided with upper 60 and lower valve-seats, 9 and 11, corresponding with valve-seats 8 and 10, on the plate D and chamber E. The valve e may be solid, with vertical perforations n, or it may be hollow in its lower part, with such perforations, 65 the pressure of the gas in either mode of construction being a vertical pressure on the outside of the valve. The disk G is a dry disk; but this valve is equally applicable to a governor in which a float-disk or a flexible dia- 70 phragm is used. The plate D has gas-exit perforations s s, as shown.

Rising vertically through screw-threaded perforations in the lower cup, B, are one or more regulating-screws, H H, the ends of 75 which are constructed that they may make a gas-tight joint with the perforations s s in the plate D, and these screws in this construction enable me to use a part of the gas-pressure as a weight and in the place of the usual weights 80 on the disk, for the reason that the gas-pressure on the under face of the disk may be more or less as the gas-flow is made smaller or greater by driving in or withdrawing, as the case may be, the ends of the regulating-screws in 85 the perforations s s of the plate D.

In Fig. 3 is shown a modification of this part of the device, adapted to burners in which a vertical rod from the governor can be extended into the burner and be heated by the 90 flame therefrom. In this arrangement the regulating-screws can be omitted, and instead thereof the plate D is cast with an extension-piece, 2, so as to form a chamber, 3, and the plate F is supplied with a vertical cylindrical extension, 4, which fits the flanged side of the plate D and the extension-piece 2, and forms a sliding valve therewith. In the piece 4 are one or more perforations, S, forming gas-exit 95 ports, and to the top of the plate F is secured 100 a rod, 6, extending into the center of the burner, this rod being hollow at its lower end, and

having gas-ports 7 to relieve the pressure on the disk of any escaping gas. It is apparent that the contraction and expansion of the rod 6 will cause the plate with its valved side to rise or fall, as the case may be, and open or close the gas-ports 5. In normal position the ports are partly uncovered. The upper plate, F, is fitted to the flanged side of the plate D to protect the disk and valve, and prevent any dirt or water falling on them and impeding their action, and where a dry disk is used the plate F is perforated in one or more places to permit the escape of gas that may find its way above the disk and exert a pressure thereon.

15 The operation is as follows: Gas from the supply-pipe enters the governor through the opening b, passing into the chamber C, within which is supported the cylindrical valve-chamber E, then around the latter and through 20 the perforations o o, strikes the vertical sides of the valve and presses against the lower face of the disk G, and out through the perforations s in the plate D, and around the same upward to the exit-opening a to the burner or burner tube.

25 When the pressure of gas is too great, the disk G will rise and bring the upper side of the valve against the central opening in the plate D, which opening is constructed to form a valve-seat, and thus more or less close the 30 exit-passage for the gas, and this operation balances the valve by forcing a part of the gas to pass around the valve e downward and out through the perforations n. The pressure can be further regulated, as described, by means 35 of the regulating-screws.

Having thus described my invention, what I claim as new, and desire to secure by Letters Patent, is—

1. In a governor for regulating the flow and 40 pressure of gas to a burner, a valve with vertical perforations, in combination with an annular gas-chamber, and a disk to close the gas-exit ports, substantially as set forth.

2. The combination of an outer annular gas-45 tight chamber, an inner annular chamber pro-

vided with exit-ports, a valve with vertical perforations and with a neck supporting a disk, and a guide-rod secured to the base of the inner chamber and serving to guide the valve and disk vertically, whereby the gas-ports to the supply-pipe of the burner are opened or closed in whole or in part by the greater or less pressure of gas within the inner annular chamber, substantially as and for the purpose set forth. 50

3. The combination of the shell A B, provided with an annular extension forming a chamber, C, the flanged plate D, provided with gas-ports and a central opening, the inner central chamber, E, provided with gas-ports and 55 a vertical guiding-rod, and the valve e and disk G, moving upon said rod and serving by the action of the gas to open or close gas-exit ports in the plate D, substantially as set forth.

4. The perforated plate F, in combination 60 with the flanged plate D, arranged and operating substantially as set forth.

5. In a gas-governor, one or more regulating-screws, in combination with the plate D, and operating to open or close, more or less, one 65 or more gas-exit ports in said plate, as set forth.

6. In a gas-governor, the combination of the cap or plate F, having a cylindrical extension, 70 4, and a rod extending into a gas-burner and to be affected by the heat therefrom, and the flanged plate D, having an extension-piece, 2, forming an annular chamber, 3, with said plate, whereby the gas-ports S and 5 are fully or partially opened to each other as the rod may be more or less expanded by the heat of the burner, 75 said parts being constructed, arranged, and operating substantially as and for the purpose set forth.

In witness whereof I have signed my name to this specification in the presence of witnesses.

THOMAS GORDON.
